UNITED STATES PATENT OFFICE.

HELEN JOHNSTON HURT, OF NEW YORK, N. Y.

METHOD OF AND COMPOSITION FOR TRANSFERRING DESIGNS, PICTURES, AND THE LIKE.

No Drawing.

Application filed September 11, 1926. Serial No. 134,947.

This invention relates to a composition for, and a method of ornamenting and decorating textiles, wearing apparel, leather goods, parchments, furniture, walls, and wood work for interior decorations and the like, by transferring or reproducing thereon designs, flowers, and other representations in water-colors of varying and controllable degree of intensity, or as a production in oil. 10 The object of the invention includes the provision of a composition of matter which is inexpensive to manufacture, and which is readily applied for transferring or reproducing designs, flowers, pictures and the like. 15 Another object includes the manner of manipulating the transferring or reproducing steps, as well as the mode of applying the composition for the purpose of transferring or reproducing the objects for ornamental, decorative, or other purposes. 20

It is among the special purposes of my invention to provide a composition of material and mode of manipulation whereby any desired degree of intensity of outstanding color 25 or configuration may be bodily transferred from its carrying or transferring surface to its final or receiving surface in clearly defined outlines and in any desired degree of intensity. The design, floral or other representation, is prepared for the purpose at hand, and the representation may be in water colors or in oil, as may be desired. In order that the best results may be obtained with widely differing materials, it is of prime 30 importance that the object to be transferred or reproduced on its transfer surface be properly prepared and suitably applied, and in some instances must the receiving surface be also prepared. While it is necessary to 35 vary the mode of procedure somewhat in order to meet specific problems, or to render certain features more effective, the basic steps and controlling principles in general, do not vary. I find also that greater intensity and more striking color effects are 40 possible by suitably preparing and intensifying the transfer design or object before the transition is made, and in general, this mode of procedure is preferred. In some 45 instances, however, it will be found that the so-called "finishing touches" can be best given to the transferred design, as for example, where the transfer is weak or indistinct and requires intensifying. In such 50 cases I effect the change by applying addi-

tional coloration in any suitable manner, as by a fine camel's hair brush. Such intensifying is often found necessary in reproducing floral decorations on delicate fabrics, or on parchments and rough surfaces. 60

In order to effect a clear and pleasing transfer, I find it also of great importance to so prepare and manipulate the design or floral decoration, as to obtain a clean-cut reproduction without any blurring or running of colors, and still retain the soft blending and merging of the colors so pleasing to the trained eye and aesthetic sense. 65

In order to more fully set forth my mode of procedure, I will now give several specific instances illustrative of my invention: 70

(A) Delicate fabrics, as silks, fine linens, hangings, or their equivalents, which may be used as articles of clothing or for decorative and other purposes. 75

If the article to be decorated is a white silk shawl or a silk or linen gown, for example, and the decoration is to be a rose or other floral design, I either produce the rose or design on a suitable backing in either water colors or in oil, or I take the selected floral design bodily from the printed object, as wall paper or the like, and properly prepare the same for the transfer. If several duplicates or facsimiles are required, I prefer to follow the latter course, as the general features are thereby more accurately and quickly obtained. Assuming now that the same design and color scheme is to be followed for several articles of clothing, that is, 80 the reproduction is to be made on fine fabrics or on smooth surfaces and materials which are very delicate, it is generally advantageous to suitably intensify the selected design before the transfer is made. If the selected design is a print on a paper backing, and is in water colors, I take an artist's brush and suitably strengthen or modify the design as may be required. If the reproduction is to be in oil, I use the proper oil paints 85 for this purpose, and then permit the oil prepared design to harden just enough to be fairly tacky. This usually takes about one to five hours. The next step in preparing the design, includes a close trimming of the 90 design as to its outline. The trimming step is necessary in either case, whether the water color product, or that in oil, is used. The design having been properly prepared, 95 is now ready to be transferred to its final 100 105 110

surface. It is understood that in case of the water color product, the prepared and trimmed design may be used at any time, while in case of the oil product, it will have 5 to be used at least within five hours after being prepared. It is further also understood that the term design, as herein used, applies to the picture or floral and other decoration or production for reproducing or 10 transferring the same on to its final surface, from, usually, its temporary surface or backing.

Having selected the surface to be decorated, which in the case of a fabric is properly supported on a fairly solid and slightly padded surface, I take the prepared design and quickly submerge the same, with face down, in my composition or transfer solution, for the purpose of providing a binding 20 medium, which, at the same time, acts so as to effect the transfer of the design without blurring or running of colors. The composition or transfer solution which I find most effective, is of a mucilaginous consistency, 25 and contains an alkali and a saponifiable oil or a fatty acid in combination, to form a soft soap like consistency. This composition is thinned out with rain or distilled water to a syrupy consistency, and serves as 30 the transfer medium, into which the designs are immersed momentarily, or just long enough to soften the color or pigment which constitutes the design or object to be transferred. After the design has been immersed 35 long enough to enable the transfer to be effected, as will be indicated by a perceptible change in appearance of the backing sheet, the design is removed from the transfer solution or medium, and excess of solution 40 removed. This should be quickly done, and may be accomplished by applying the design to a blotting or like surface. The design is now placed, face down, on the prepared receiving surface for manipulation to 45 effect a clean cut and complete transfer of the entire design in all its varied or desired details. This manipulation includes the steps of first causing the edges of the design to be brought into intimate contact with the 50 receiving surface before the main or body part of the design is caused to adhere and be transferred. By following these sequences of manipulation, I obtain a clean cut and clear outline of the design, with no blurring 55 or running of colors. I find the most effective way to thus manipulate the transfer by covering the entire design back and adjacent material with a clean cloth or paper, and then by means of a hard object, as a 60 silver or pewter spoon handle, follow the outline of the design along its outer edges. I next apply considerable frictional pressure to the entire surface of the design, by means of a rounded vitreous surface to thereby 65 produce frictional heat, and, I believe, static

electricity. The manipulation must be vigorous and intense enough to produce a complete transfer, which usually is effected when the receiving surface and design have become warmed and dried. It is believed that 70 during the steps of manipulation a possible chemical change takes place by means of which the transfer is rendered complete and effective. After the transfer has been completed, the cover and backing sheets are 75 removed, and the article is decorated and ready for use. In case, however, additional intensifying of color is necessary, the same can be supplied by an artist's brush in the manner indicated for the preparation of the 80 original design.

(B) For coarse surfaces, as woolen fabrics, or for parchments, leather goods, and the like, I find that the color-backing, whether as water colors or in oil, must be more 85 pronounced and heavier, to reproduce in clear and pleasing outlines. The manipulation steps must also be more intense than in (A).

(C) For wall decorations, furniture, wood 90 surfaces and the like, it is necessary to modify the steps under (A) or (B) in accordance with the surface to be decorated, and the surface itself is necessarily prepared by fillers, or suitable coverings, to produce 95 the proper receiving surface. It is also important that the design be properly prepared with just enough coloring material to reproduce the same in the desired degree.

The transfer solution of a consistency 100 above specified, should be alkaline in reaction, and may be made by saponifying a suitable vegetable oil, as olive oil, palm oil, or cottonseed oil, with an alkali, as potassium or sodium hydroxid and prepared lye 105 in solution in the presence of gentle heat, until the saponification is complete. The mixture is then diluted with water and allowed to cool. If necessary, after cooling, it is further diluted as stated above. It will 110 keep well in stoppered bottles, and can be used as needed.

While I have given specific examples to illustrate my invention, I do not thereby desire to be understood as having thus limited myself unduly.

What I claim therefore, as new and useful, of my own invention, and desire to secure by Letters Patent is:—

1. The method of ornamenting materials 120 with a design ornamentation which comprises preparing said design, then immersing said design in a transfer solution, and bringing said design after immersion into contact with the receiving surface of the 125 material to be ornamented, and manipulating said design to effect the transfer.

2. The method of ornamenting materials with a design ornamentation which comprises preparing said design and trimming 130

the edges thereof to form a sharp outline, then immersing said design momentarily in a transfer solution, then causing the edges of said design to be brought into contact with the receiving surface to be ornamented thereby causing the edges of the design to adhere to said surface, and finally applying the surface of the design within its edges to the receiving surface.

10 3. The method of ornamenting materials with a design ornamentation which comprises preparing said design and trimming the same to form a sharp outline, then subjecting said design to a transfer solution in limited quantities, then causing said design to be brought into contact with the material to be ornamented, and causing the edges of the design to be manipulated, and finally manipulating the entire surface of the design to cause the transfer to be effected.

15 4. The method of ornamenting a receiving surface which comprises preparing a design to be applied to said surface, then immersing the prepared design in a transfer solution, and causing the design after immersion to be applied from its outer edges inwardly to the receiving surface, to thus transfer the design thereto.

20 5. The method of ornamenting a surface which comprises preparing an ornamenting design, then immersing said design in a transfer medium, then, after immersion, placing the design face downward upon the surface to be ornamented, then applying pressure 25 over the edges of the design, and finally applying pressure throughout the area of the design within its outer edges to cause the design to be transferred to said surface.

30 6. The method of ornamenting a surface

which comprises selecting a design and applying color material to said design, then immersing said colored design in a transfer medium and pressing the same, after immersion, upon the surface to be ornamented, to cause said color material to be transferred 40 to said surface.

45 7. The method of ornamenting a surface which comprises selecting a design and applying color material to said design, then immersing said colored design in a transfer medium, and placing the same, after immersion, upon the surface to be ornamented, and finally applying frictional manipulation thereto to effect transfer of the colored design to said surface.

50 8. The method of ornamenting a surface which comprises selecting a design and applying color material to said design, then trimming the design and immersing the same in a transfer solution, then applying the design to said surface, then causing the outer edges to be brought into intimate contact with the receiving surface, and finally causing the remainder of the design to be manipulated to completely transfer the 55 design.

60 9. A transfer solution comprising a vegetable oil, an alkali in chemical union and diluted to a syrupy consistency.

65 10. A transfer solution comprising a saponifiable body, consisting of a vegetable oil, and an alkali chemically united and diluted to syrupy consistency, and serving as a binder and transfer medium.

70 In testimony whereof I have hereunto set my hand on this 10th day of April, A. D., 1926.

75 HELEN JOHNSTON HURT.
